UNITED STATES PATENT OFFICE.

WILLIAM H. MINER, OF CHAZY, NEW YORK.

BUMPER FOR RAILWAY-CARS.

1,290,282.

Specification of Letters Patent.

Patented Jan. 7, 1919.

Application filed May 19, 1917. Serial No. 169,766.

To all whom it may concern:

Be it known that I, WILLIAM H. MINER, a citizen of the United States, residing at Chazy, in the county of Clinton and State 5 of New York, have invented a certain new and useful Improvement in Bumpers for Railway-Cars, of which the following is a full, clear, concise, and exact description, reference being had to the accompanying 10 drawings, forming a part of this specification.

My invention relates to improvements in bumpers for railway cars.

The object of my invention is to provide a 15 high capacity and efficient bumper especially adapted to be associated with a bumping post.

In the drawings forming a part of this specification, Figure 1 is a vertical longitudinal section of a bumping post with the shock absorbing mechanism mounted therein and embodying my invention; Fig. 2 is a cross section taken on line 2—2 of Fig. 1; Fig. 3 is a cross section taken on line 3—3 25 of Fig. 1; and Figs. 4 and 5 are longitudinal, vertical, central sections of the buffer device proper shown in Fig. 1. Fig. 4 showing the position of the elements under full release, and Fig. 5 the position assumed at 30 the end of the compressive stroke.

Referring to the drawings, the numeral 10 indicates a railroad tie, 11 the ends of a rail associated therewith, forming the end of a railroad track at which is mounted the 35 bumping post 12 formed of suitable material, as for instance, concrete, as illustrated in the drawings, suitably reinforced by the steel members 13. In said bumping post, a forwardly opening pocket 14 is provided to 40 receive the shock absorbing mechanism 15. The said mechanism comprises an outer casting 16, preferably cylindrical in form, and comprising the two sections 17 and 18 provided at their meeting edges with the flanges 45 19, suitably secured together by the bolts 20. Within said casing 16 is mounted a sliding shell 21 provided at its forward end with the out-turned flange 22 forming a seat for the forward ends of the springs 23 which are 50 annularly arranged about the sliding shell 21 and between it and the casing 16. At their inner ends the springs 23 are seated against wedge blocks 24 which with the friction shoes 25 form friction mechanism adapt- 55 ed with the springs to resist the inward movement of the sliding casing 21. The

said friction shoes are each provided with a friction face 26 engaging the adjacent friction face 27 of a wedge 24, and at their opposed ends the said friction shoes are provided with the friction faces 28 adapted to engage against the wedge friction face 28 with which the outer casing is provided near its inner end. The outer casing 16 is provided with an inner end wall 29 permitting 60 the passage of a tool or suitable bar. A perforation 31 is extended through the bumper post terminating at the said wall 29 to permit the insertion of a suitable tool, as for instance, a bar with which the casing 16 and 65 the contained parts can be driven from the pocket 14 in the bumper post should it be found desirable to remove the same. Within the sliding casing 21 is mounted a primary compression resisting member comprising a shell 33 containing the springs 34 intermediate its ends, the springs being associated at either end with a set of friction elements 35, the said friction elements comprising shoes 36 adapted to engage the friction surfaces 37 of the shell and a wedge 38, anti-friction rollers 39 being mounted between the wedging faces 40—40 of the wedge and the adjacent wedging faces 41 of the 70 shoes. 75

At its forward end the primary compression resisting member is provided with a cap or bumper block 42 against which the coupler of an approaching car is adapted to engage, and at its inner end with a similar 90 cap 43 which is adapted to engage against the buffering head 44 upon suitable inward movement of the sliding shell and the compression of the secondary compression resisting members hereinbefore described as 95 mounted between the sliding shell 21 and the outer casing 16. 85

Upon the approach of a car, the coupler, projecting from its end engages against the cap or bumper block 42, driving the primary 100 compression resisting member rearwardly, the primary compression resisting member carrying with it on inward movement the sliding shell 21 which is provided with the spaced-apart annular flanges 105 45—45 near its forward end to receive between them the annular outstanding flange 46 with which the shell of the primary compression resisting member is provided, and near its rear end with the flange 47 against 110 which the rear outstanding flange or collar 48 of the shell of the primary compression

resisting member abuts. By reason of this engagement of the primary compression resisting member with the sliding shell, the sliding shell is moved rearwardly, its rearward movement being resisted by the springs 23 and the frictional resistance of the friction members against which the said springs are seated at their rearward ends. Upon suitable inward movement, the resistance afforded by the secondary compression resisting members is augmented by that of the primary compression resisting members when the inner cap 43 engages against the member 44 at the rear end of the outer casing 16, as shown in Fig. 5. The combined resistance of these parts in a device of suitable size may be made to exceed 1,500,000 pounds.

Although I have herein shown and described what I now consider the preferred embodiment of the invention, the same is merely illustrative, and I contemplate all changes and modifications that come within the scope of the claims appended hereto.

25 I claim:

1. In a bumper, the combination with a fixed abutment, of primary and secondary shock absorbing mechanisms supported by said abutment, the primary shock absorbing mechanism being bodily movable, said secondary shock absorbing mechanism including a plurality of springs interposed between said abutment and portions of the primary shock absorbing mechanism.

35 2. In a bumper, the combination with a fixed abutment, of a primary friction shock absorbing mechanism and a secondary friction shock absorbing mechanism both supported by said abutment, the primary shock absorbing mechanism being adapted to actuate the secondary shock absorbing mechanism, said secondary shock absorbing mechanism being disposed around the periphery of the primary shock absorbing mechanism.

45 3. In a device of the character described, the combination with a double ended friction primary shock absorbing mechanism, said mechanism being bodily movable, of means for supporting said shock absorbing mechanism, and additional shock absorbing mechanism interposed between said means and said friction shock absorbing mechanism.

55 4. In a device of the character described, the combination with an abutment, of a shock absorbing mechanism, a movable casing within which said mechanism is carried, a fixed shell carried by said abutment, and friction elements interposed between said shell and said casing and coöperable with both to thereby cushion movements of said casing and the shock absorbing mechanism carried thereby.

65 5. In a device of the character described, the combination with an abutment, of a

shock absorbing mechanism, a movable casing within which said mechanism is carried, said casing comprising a plurality of independent segments, a fixed shell, and friction elements interposed between said shell and said casing adapted to cushion movement of said casing and the mechanism carried thereby.

6. In a device of the character described, the combination with an abutment, of a friction shock absorbing mechanism including a friction shell, a movable casing within which said friction shell is carried, coöperating engaging shoulders on said shell and casing, an outer fixed shell, and means interposed between said outer shell and said casing adapted to cushion movements of the latter and the friction shell carried within the casing.

7. In a device of the character described, the combination with an abutment, of a double ended friction primary shock absorbing mechanism including a friction shell, a casing within which said friction shell is carried, said casing being movable, a fixed outer shell, and cushioning means interposed between said outer shell and said casing.

8. In a device of the character described, the combination with an abutment, a fixed shell carried by said abutment, said shell being open at one end, of a casing mounted within said shell, said casing being bodily movable and comprising a plurality of independent elements, shock absorbing means interposed between said casing and said fixed shell to cushion the movements of said casing, and additional shock absorbing means carried by and bodily movable with said casing.

9. In a device of the character described, the combination with an abutment, of a fixed shell carried by said abutment, a casing comprising a plurality of independent segments mounted within said shell, friction elements interposed between said casing and said shell to thereby cushion the movements of said casing, and a friction shock absorbing mechanism carried by said casing and adapted to actuate the latter.

10. In a device of the character described, the combination with a fixed abutment, of a fixed cylindrical shell mounted within said abutment, a collapsible cylindrical casing slidably mounted within said shell, a circularly arranged series of friction shoes and wedges coöperable with said casing and shell to cushion movements of the casing within the shell, and shock absorbing mechanism carried within and movable bodily with the casing.

11. In a device of the character described, the combination with a fixed abutment, of a fixed shell mounted within said abutment, the shell being open at its outer end and having wedging surfaces at its inner end, of

a casing comprising a plurality of segments slidably mounted within said shell, a circularly arranged series of friction shoes and wedges coöperable with the outer surface of the casing and the inner surface and wedging surfaces of the shell, springs interposed between some of said friction elements and the casing, a double ended friction shell mounted within and movable in unison with

said casing, friction elements coöperable 10 with each end of said double ended shell, and spring means interposed between said friction elements and carried by the shell.

In witness that I claim the foregoing I have hereunto subscribed my name this 15th 15 day of May, 1917.

WILLIAM H. MINER.
